UNITED STATES PATENT OFFICE.

CHARLES F. GOETTHEIM, OF CINCINNATI, OHIO.

DESIGN FOR A SPOON.

SPECIFICATION forming part of Design No. 21,142, dated November 3, 1891.

Application filed May 11, 1891. Serial No. 392,539. Term of patent 3½ years.

To all whom it may concern:

Be it known that I, CHARLES F. GOETTHEIM, a citizen of the United States, and a resident of Cincinnati, in the county of Hamilton and 5 State of Ohio, have invented and produced a certain new and useful Design for Spoons, of which the following is a specification, reference being had to the accompanying drawing, forming part thereof.

10 The object of my invention is to provide a spoon so designed that as a whole it will present a neat, beautiful appearance, and that the several parts which go to make up the general design will be emblematic of the city 15 of Cincinnati, Ohio, or, in other words, that a spoon of my design, in addition to its elegant appearance as a spoon, will be a souvenir of said city.

The accompanying drawing is a front elevation of a spoon fully illustrating my design. 20 The leading features of my design consist

in forming the handle of the spoon to represent a branch of the Ohio buckeye-tree, the top of the handle being a figure of Cincinnatus, with the conventional plow. The stem 25 A, at its junction with the bowl B, branches from the center, the bracket-supports for the bowl being two buckeyes *a a*. Upon top of the branch A is a representation of an official seal, and above this a molded pedestal D, 30 upon which the figure E of Cincinnatus is mounted.

Within the bowl of the spoon is a representation of a fountain.

What I claim is— 35
The design for a spoon, as herein shown and described.

CHAS. F. GOETTHEIM.
